UNITED STATES PATENT OFFICE.

HARRY B. STAVER, OF CHICAGO, ILLINOIS.

RACING-TRACK APPARATUS.

Application filed January 13, 1927. Serial No. 160,807.

This invention relates to racing track apparatus and it has particular relation to racing tracks on which dogs are induced to run by means of a lure propelled in front of the same.

One object of the invention is the provision of an improved tunnel construction or housing for enclosing and concealing the lure carriage and the rail track on which the same is running.

The invention will be best understood from the following description of an exemplification of my invention, reference being made to the accompanying drawings in which

Fig. 1 is a plan view of a racing course in connection with which my invention is used; and

Fig. 2 is a vertical sectional view of the housing embodying my invention.

In order to train racing dogs, or similar animals, and to improve their racing qualities, a racing track 10, as shown in Fig. 1, is provided and dogs are induced to run on said track by driving in front of the same an artificial rabbit or lure 11, shown in Fig. 2. The lure 11 is usually carried along the track by means of a carriage 12 which is propelled on a rail track 13 running parallel adjacent to the racing track 10, a lure arm 14 serving to support the lure from the carriage.

At a convenient point adjacent to the track there is usually provided a grandstand for the spectators which are interested in observing the races.

For the satisfactory operation of such races it has been found desirable to conceal or cover the lure carriage and the carriage track in a suitable housing or tunnel 21. One reason for using the tunnel is the desire to confine the attention of the dogs to the lure and prevent them from jumping into the rail track where they would be liable to injury by the electric supply wires or the carriage mechanism. It is also desirable to concentrate the attention of the spectators on the portion of the racing track on which the dogs are running behind the lure and in general to give the entire track a more attractive appearance.

A tunnel or housing construction which secures the foregoing objects and which is at the same time cheap and simple to build and maintain, is shown in detail in Fig. 2 of the drawing.

In the arrangement illustrated in the

drawing the rail track is disposed on the inner side of the racing ground. This is a construction which I now prefer, although the improvements described hereinafter are equally applicable to constructions wherein the rail track is disposed on the outer side of the racing track. The level of the rail track 13 is at such height below the level of the racing track 10, that, when the carriage 12 is in normal position on the rail track 13, the projecting lure arm 14 holds the lure 11 just above the ground of the rail track 10. A plurality of rail ties 22 are disposed at intervals along the rail track, a pair of rails 23 for guiding the carriage wheel, and a third rail supply conductor 24, being suitably secured to the ties.

The tunnel or housing comprises an outer wall 25 on one side of the rail track, an inner wall 26 disposed on the other side of the rail track and a roof 27 extending over the space between said two walls. The outer wall of the track wall 25 is made of a plurality of spaced posts 31 suitably set in the ground, and boards 32 nailed, or otherwise secured, to the post lengthwise the track to support the ground of the adjacent racing track.

The inner wall 26 is similarly made of posts 35 set in the ground along the inner side of the rail track and boards 36 secured to said post. The roof 27 is supported on the last-mentioned inner wall 26 and comprises a plurality of rafters 38 held on the topmost end of the inner wall 26, the rafters 38 being covered by boards 39 which form the roof covering. The roof may be slightly slanted, as shown in the drawing, and is so arranged that the outer edge thereof hangs freely above the upper end of the inner wall 25. A continuous opening or slot is thus provided at the track side of the housing thereby permitting the lure arm 14 to be freely carried around the track. In order to make the tunnel or housing as inconspicuous as possible and with a minimum cost, it is desirable that the heights of the housing shall be small, just enough to permit free movement of the carriage within the same.

The construction shown in the drawing secures the last-mentioned object in a novel manner. According to my invention the roof 27 is firmly supported on the inner side wall 26 without the use of inner bracing members unnecessarily increasing the clearance required for the operation of the carriage with-

in the tunnel, and without upwardly projecting unsightly posts. To this end the roof 27 has inwardly projecting extensions 41, preferably as extensions of the rafters 38.

5 The free ends of the rafter projections 41 are held in place by means of truss rods or bracing members 42 which are suitably anchored in the ground, preferably inside the tunnel, to points on the rail ties 22.

10 The truss rods 42 may be provided with turn buckles 43, preferably disposed within the interior of the housing 21 for retaining the roof in the desired position. The roof or rafter extensions 41 may also be supported 15 against the wall 26 by means of braces or tie pieces 44 extending between said extensions and the posts 35 on the inner wall 26. The braces may be used conjointly with the truss rods 42, or the latter may be entirely 20 omitted.

The above described construction of the housing makes it possible to have the roof very low above the carriage resulting in an extremely small housing. The roof position 25 may be conveniently adjusted from inside of the housing by merely turning the buckle 43 which is disposed at a convenient place near the bottom of the housing.

I claim as my invention:

30 1. In an animal racing course comprising a racing track, a carriage track disposed on one side of said racing track, a carriage arranged to be driven on said carriage track and a lure carried on said racing track by said carriage to induce dogs to run therebehind, a housing for covering said carriage track, said housing comprising a wall disposed on the side of the carriage track opposite said racing track and a roof supported 35 on said wall to provide a continuous opening on the side of the housing adjacent said racing track, said roof having extensions on the side of the wall opposite said tracks, and means for bracing said extensions against 40 said wall below said roof to hold said roof in fixed position.

2. In an animal racing course of the type comprising a rail track disposed on one side of said racing track, a carriage arranged to be driven on said rail track and a lure carried on said racing track by an arm extending from said carriage to induce dogs to run therebehind, a housing for covering said rail track comprising a wall disposed on the side of the rail track opposite said racing track and a roof extending above said rail track and having one side supported on said wall, the other side of said roof hanging freely above said rail track to provide a continuous opening for said arm, said roof having extensions on the side opposite said racing track, and truss rod means extending between said extensions and the ground adjacent said rail track below said roof.

3. In an animal racing course comprising 65 a rail track disposed on one side of said racing track, a carriage arranged to be driven on said rail track and a lure carried on said racing track by an arm extending from said carriage to induce dogs to run therebehind, a housing for covering said rail track comprising a wall disposed on the side of the rail track opposite said racing track and a roof extending above said rail track and having one side supported on said wall, 70 the other side of said roof hanging freely above said rail track to provide a continuous opening for said arm, said roof having extensions on the side opposite said racing track, and truss rod means having one end secured to a point on said extensions and another end secured to a point on said rail track within said housing. 75

4. In an animal racing course comprising 80 a rail track disposed on one side of said racing track, a carriage arranged to be driven on said rail track and a lure carried on said racing track by an arm extending from said carriage to induce dogs to run therebehind, a housing for covering said rail track comprising 85 a wall disposed on the side of the rail track opposite said racing track and a roof extending above said rail track and having one side supported on said wall, the other side of said roof hanging freely above 90 said rail track to provide a continuous opening for said arm, said roof having extensions on the side opposite said racing track, and a truss connection having one end joined to a point on said extension and another end joined to a point on said rail track within 95 said housing, said truss connection being inclined and having means for adjusting the length thereof, said means being on the 100 part of said connection disposed within said housing. 105

5. In an animal racing course wherein an artificial lure is carried on said course to induce dogs to run therebehind, a dog racing track, a rail track disposed alongside said racing track at a level below the same, a housing for covering said rail track, said housing comprising a wall disposed on the side of the rail track opposite said racing track, a roof extending above said rail track and having one side supported on said wall, the other side of said roof hanging freely directly above the edge of said rail track to provide a continuous opening therearound, 110 said roof having extensions on the opposite side of said racing track, and means for bracing said extensions against said wall below said roof to hold the roof in fixed position. 115

In witness whereof I have hereunto subscribed my name.

HARRY B. STAVER.
